Inventor
Julius S. Caine
or Orvay & Bair

UNITED STATES PATENT OFFICE.

JULIUS S. CAINE, OF DES MOINES, IOWA.

DUPLEX ENVELOP.

1,381,793.

Specification of Letters Patent. Patented June 14, 1921.

Application filed August 11, 1919. Serial No. 316,896.

To all whom it may concern:

Be it known that I, JULIUS S. CAINE, a citizen of the United States, and a resident of Des Moines, in the county of Polk and State of Iowa, have invented a certain new 5 and useful Duplex Envelop, of which the following is a specification.

The object of my invention is to provide a duplex envelop of simple, durable and inexpensive construction.

10 A further object of my invention is to provide an envelop whereby goods which may be carried by parcel post may be shipped in a suitable envelop having attached thereto a second envelop adapted to receive first-class mail, such for instance, as the 15 invoice or letter accompanying the goods.

A further object of my invention is to make such an envelop, which is so arranged that the entire envelop may be formed from 20 a single blank with a minimum number of processes.

A further object of my invention is to provide an envelop of the type described, having fastening devices mounted thereon, 25 whereby the goods in the merchandise or catalogue portion of the envelop may be attached to the letter holding portion of the envelop in such a way that even though a portion of the former part of the envelop 30 becomes torn then the fastening device will keep the two parts together.

With these and other objects in view my invention consists in the construction, arrangement and combination of the various 35 parts of the device, whereby the objects contemplated are attained, as hereinafter more fully set forth, pointed out in my claims, and illustrated in the accompanying drawings, in which:

40 Figure 1 shows a top or plan view of the blank from which my envelop is made.

Fig. 2 shows a top or plan view of the envelop after it has been folded and the flaps sealed, so that it is ready to receive 45 merchandise or catalogues and a letter or invoice.

Fig. 3 shows a plan view of the envelop after the envelop has been folded as it would be after the appropriate articles have been 50 placed therein, and also illustrating the manner of holding the merchandise or catalogue therein from becoming separated from the envelop.

Fig. 4 shows a longitudinal, enlarged, 55 sectional view taken on the line 4-4 of Fig. 3; and

Fig. 5 shows an enlarged, detail, sectional view of the fastening device.

Referring to the accompanying drawings, 60 I have used the reference numeral "A" to indicate generally the blank from which my improved duplex envelop is formed.

The original blank is substantially rectangular in shape, and is indicated by the 65 dotted lines 10. The blank in its rectangular form is run through suitable dies or cutting devices, whereby the flaps 11, 12 and 13 are formed and at the same time an arcuate cut 14 may be made at one end of 70 the blank.

The same or different processes may also form creases 15, 16, 17 and 18 and the creases 19 and 20.

It will be understood that the creases 75 15 to 18 inclusive are intended to indicate and outline the folds forming the edges of the envelop, while the creases 19 and 20 form the ends of the envelop.

When the blank has been formed with the 80 flaps and creases described, it will be seen that it is divided into four sections, namely "B," "C," "D" and "E."

In order to form a catalogue holding envelop, the section "E" is folded on the crease 85 18 over onto the section "D" and the flaps 13 are folded upon the creases 20 to lap over the side edges of the portion "E," so that when suitable gum is applied to the 90 under surface of the flaps 13, they may be sealed against the portion "E" to form an envelop open at the top.

In this connection, it will be noted that the arcuate cut 14 is at the top or receiving end of the envelop, it being formed for 95 a purpose, which will hereinafter be set forth.

In order to form the letter or invoice holding portions of the envelop, the portion "B" is folded on the crease 16 over onto the 100 portion "C" and the flaps 12 are turned on the creases 19 over the side edges of the portion "B" and suitable gum applied to seal the lower surface of the flaps against the upper outer edges of the portion "B." 105

The flap 11 is gummed on what would be the upper surface of the blank "A" in the position shown in Fig. 1 and it will be seen that when the portion "B" is folded over the portion "C," then the gum surface of the 110 flap 11 will be disposed adjacent to the edge 14 of the portion "E."

I preferably form a sealing or tying device for my envelop, which may be in the

2
form illustrated in Fig. 5. In this form of sealing or tying device, an eyelet 21 is let into the portion "C" adjacent to the closed end of the letter holding envelop and 5 has two spaced washers 22 and 23 mounted thereon.

Between the washers 22 and 23, a string or other flexible device 24 is tied around the eyelet 21, the string being of such length 10 that it may be drawn around the envelop along lines parallel with the transverse and longitudinal axes thereof.

In the portion "A", a second eyelet 25 is let into the portion in position to substantially register with the eyelet 21 when the envelop is folded into position shown in the 15 Figs. 3 and 4, and the eyelet 25 carries the spaced washers 26.

In the practical operation of my improved 20 device, the blank is formed as is illustrated by the full lines in Fig. 1 with the creases heretofore mentioned therein, and then the portions "B" and "C" and "D" and "E" are folded together to form the letter or invoice 25 receiving envelop and the catalogue or merchandise receiving envelop, so that the parts will assume substantially the position shown in Fig. 2.

The flap 11 may then be raised to slip in 30 the letter or invoice into the letter receiving portion of the envelop and the curved end 14 may be raised to permit merchandise or catalogues to be slipped into the appropriate portion of the envelop.

35 The gum flap 11 is then moistened and the flap inserted under the curved end of the portion "E", and the device is then folded upon the creases 15 and 17 to assume substantially the position shown in Fig. 3.

40 The finger may be run along the end of the portion "E" or the device may be grasped after being folded to the position shown in Fig. 4, and the fingers run along the outside of the portions "A" and "C" to insure 45 that the gum on the flap 11 has properly sealed against the portion "D".

Suitable reference or indicating characters may be placed upon the portion "C" adjacent to the crease 17 to indicate to the 50 recipient of the envelop the manner of opening same, which may be accomplished by inserting a knife between the flap 11 and the portion "B" and cutting across the envelop, which will sever the blank along the creases 55 15 and 17, thereby separating the first and second class envelopes and simultaneously opening both of them, so that the contents thereof may be removed.

It will be noted that the curved portion 60 14 permits ready access to the merchandise holding portion of the envelop when the latter is to be opened and also makes it easier to insert the flap 11 beneath the end of the portion "E".

65 Means are provided for holding the in-

voice compartment and the merchandise compartment together, comprising the flexible device 24, which may be extended around the envelop along its longitudinal axis and then wound around between the 70 washers 22 and 23 so that the compartments may be held from movement relative to each other and the merchandise compartment sealed.

It may also be desirable to form the flexible 75 device 24, so that it is of sufficient length to extend around the envelops, both along their longitudinal axes and along their transverse axes, in which case the flexible device is also looped around the eyelet 25 on the bottom 80 of the envelop, so that the string will not slip off from the corners of the envelop, or otherwise become displaced.

Other forms of fastening devices, which accomplish the same result, may be also 85 used, but it is to be noted that where the string fastening device is used, then even though the merchandise compartment becomes torn, the string will prevent the separation of the merchandise from the remaining portion of the envelop.

Some changes may be made in the construction and arrangement of my improved device without departing from the real purpose and spirit of my invention, and it is my 95 intention to cover by my claims any modified forms of structure or use of mechanical equivalents, which may be reasonably included within their scope.

I claim as my invention:

1. In a device of the class described, an envelop formed from a single blank by folding the ends of the blank upon the central portions to thereby form independent compartments, sealing flaps adapted to close the 105 ends of said compartments and a flap formed at one end of said blank adapted to extend past the line upon which said compartments are folded, when one is swung over to position where it is superimposed upon the 110 other.

2. In a device of the class described, an envelop formed from a single blank by folding the ends of the blank upon the central portions to thereby form independent compartments, sealing flaps adapted to close the 115 ends of said compartments and a flap formed at one end of said blank adapted to extend past the line upon which said compartments are folded, when one is swung over to position where it is superimposed upon the other, said flap having a gummed portion adapted to engage the material of the blank adjacent to its central portion, 120 whereby when the compartments are folded upon themselves, a cut made along the fold may simultaneously open both compartments.
